MACHINE FOR CALCULATING AVOIRDUPOIS WEIGHTS

Denis Harold Bates, Earlsfield, London, England, assignor to The National Cash Register Company, Dayton, Ohio, a corporation of Maryland

Application September 9, 1953, Serial No. 379,184

18 Claims. (Cl. 235—133)

This invention relates to calculating machines and more particularly to machines for effecting calculating of weight according to the avoirdupois system of measurement.

In adapting calculating machines, having a normal decimal keyboard, for weight calculation in avoirdupois, considerable difficulties are encountered in regard to the complex transfer arrangements required between the various wheels of the totalizer, and in particular, in relation to the pounds and quarters denominations. For example, the machine must have facilities for the entry of from 1 to 9 pounds in the units of pounds keybank, 10 and 20 pound units in the tens of "pounds" keybank, and 1 to 3 in unit "quarters" in the quarters keybank, the "quarters" being of twenty-eight pounds each.

Thus, considering entries into the units of pounds keybank, the units wheel of the totalizer will continue to add with two normal transfers at 10 and 20. From this point, the units wheel can only continue to add a further seven pounds, whereupon, with the entry of the next unit, a transfer must be carried through to the quarters wheel, the units wheel caused to skip the 8 and 9 positions to zero or beyond, and also the tens of pounds zeroised or taken beyond, dependent on the amount added. This involves four different types of transfers which may be analysed as follows:

Firstly, when the units of pounds wheel of the totalizer passes from "9" to "0," "1" must be transferred to the tens of pounds wheel when the latter is standing at "0" or "1."

Secondly, when the tens of pounds wheel of the totalizer is standing at "2" and the units of pounds wheel passes from "7" to "8," that is, to effect the registration of one quarter, two units must be added to the latter wheel to bring it to "0."

Thirdly, simultaneously as the second transfer described above takes place, one unit must be added to the tens of pounds wheel, bringing it from "2" to "0," and as this occurs, the fourth transfer is effected, i. e. one unit must be transferred to the quarters wheel.

For example, if 9 pounds are firstly entered into the machine, and 1 pound is added, the units of pounds wheel will return to "0," whereas the tens of pounds wheel will be advanced from "0" to "1." If a further 9 pounds are added, the totalizer will obviously register 19 pounds.

However, if a further 1 pound is added, the units of pounds wheel will be advanced from "9" to "0" and transfer will occur to the tens of pounds wheel, bringing the latter from "1" to "2," the totalizer thus registering 20 pounds. Further unit pound registrations will occur up to 27 pounds.

With the addition of a further 1 pound, the units of pounds wheel will be advanced two steps, i. e. from "8" to "0" and simultaneously the tens of pounds wheel will be advanced from "2" to "0" while transfer occurs from this latter wheel to the quarters wheel to advance it from "0" to "1." Thus the totalizer will be registering 1 quarter 00 pounds.

2

The above transfer movements will occur until 3 quarters 27 pounds are shown in the indicator, but should 1 pound be added thereto, the above four transfers will be repeated. However, the addition of "1" to the quarters wheel will cause it to transfer "1" to the units of hundred-weights wheel, the hundred-weight being of one hundred and twelve pounds, so that the totalizer would be registering 1 hundred-weight, 0 quarters, 00 pounds.

Accordingly the invention comprises a machine for effecting calculations according to the avoirdupois system of measurement, including a totalizer and actuators therefor, the units of pounds actuator normally adding "nine" but being capable of an additional movement to add an additional amount into the units of pounds totalizer wheel, transfer mechanism associated with the units of pounds totalizer wheel, and a pair of stop-members adapted to block the path of the units of pounds actuator and thereby prevent the additional movement thereof, one of said members being under the control of the units of pounds totalizer wheel and disabled when said wheel passes through its "eight" and "nine" positions, while the remaining member is disabled when the tens of pounds totalizer wheel passes through its "two" to "zero" positions, thereby enabling the units of pounds actuator to make the additional movement to advance the units of pounds totalizer wheel to "zero" or beyond, dependent upon the resultant.

In regard to subtract entries the two stop members are operative from the tens of pounds totalizer wheel whereby the complement of the true amount is registered in the totalizer.

The above, and other subsidiary features of the present invention as applied by way of example only, to one manner of carrying it into effect, are applied to a machine of the general type disclosed in application for United States Letters Patent Serial No. 171,118 of Carl H. Carlson et al., which was filed June 29, 1950, and which is issued as United States Patent No. 2,666,574, will now be described, with reference to the accompanying drawings.

In the drawings:

Fig. 1 is a perspective view of the complete machine.

Fig. 2 is a diagrammatic vertical section, through a typical denominational order of the machine, from front to rear, showing the digit keyboard and the differential totalizer and printing mechanism, other portions of the mechanism being omitted for clarity.

Fig. 3 is an exploded perspective view of the mechanism for accomplishing the calculations in the avoirdupois system.

Figs. 4-11 are various detail views, the purpose of illustration of which will be made apparent in the following description.

General description

The machine is housed in a casing 10 (Fig. 1) having a viewing window 11, through which the number wheels of the totalizer are visible. There are ten denominational orders of digit representing keys 12 projecting through a cover plate 13 on the casing 10, the first five rows, reading from left to right, appertaining to "tons," the next two rows to "hundred-weights," the next row to "quarters," and the final two rows to "pounds."

Items to be added or subtracted are set up on the keyboard and the machine is set into operation by depressing an "add" control key 14 if an add operation is desired, or by depressing a "subtract" control key 15 for a subtract operation.

The key 16 is for taking sub-totals, the key 18 for "non-add" control, and the key 19 for effecting the "correction" control used to release any depressed digit keys. A set of type bars 20 (see Fig. 2) prints items, totals, and symbols, on a tally roll 21 held in a paper carriage 22.

The machine automatically takes and prints true positive totals, upon the depression of a common total-taking key 17, and means may be provided whereby depression of said key will take and print true negative totals.

Differential mechanism

Secured between the front ends of the right vertical side plate (not shown) and the front end of the left vertical side plate of the machine, is a normal slotted plate or comb (also not shown) in which the front ends of a series of denominational order stop bars 23 (Fig. 2), one for each denominational order, are guided and supported for sliding motion.

As the stop bars of all orders are similar, a typical order only is shown in Fig. 2 as an example.

The bar 23 is pivoted at the rear end, by a stud 24, to the upper extending arm of a three-armed diverging lever 25 pivotally mounted on a shaft 26, and is urged forwardly in known manner by a spring (not shown) applying tension approximately midway therealong, but is held against such movement by means of a bail 27 (Fig. 2) extending across the front of all the diverging levers. All of the diverging levers, with the exception of the two lowest orders, are similar to those disclosed in the mentioned United States Letters Patent of Carl H. Carlson et al., i. e. an integral rearwardly extending arm of each lever is indirectly pivoted to an associated printer type-bar.

However, in regard to the levers associated with the two lowest orders the rearwardly extending arm is not integral, but in lieu thereof, each has a rearwardly extending portion 28 (see Fig. 2) which is coupled, by a spring 29, to a lever 30 immediately adjacent thereto and freely mounted on the shaft 26, the portion 28 being bent at 31 so as to be immediately beneath said lever 30.

The lever 30 is pivoted to one arm of a U-shaped adjusting link 32, the other arm of which is pivoted on a stud 33 of a printer type-bar 34 where it is retained by a spring clip 35.

Mounted on the upper end of each diverging lever is a toothed rack 36 adapted to be engaged by an associated totalizer pinion as described in greater detail hereinafter. The racks are adapted to move forwardly by an amount dependent upon the movement of their associated stop bars, and the former, as described in greater detail in the Carlson patent, to which reference has been made, are each spring-loaded to be capable of an additional movement forwardly by one position to effect a transfer into the next bank, this being the case with all the racks with the exception of the two lowest orders, i. e. the units of pounds and tens of pounds.

The stop bars 23 associated with the units and tens of pounds are restored at each machine operation a further distance towards the rear of the machine than the remaining bars, and the spring coupling 29 will thus permit this continued movement after the downward movement of the type-bars has been arrested. The type bars 34 are vertically adjusted in known manner with respect to the paper platen 37, shown diagrammatically, according to the selective positioning of the diverging levers under control of the digit keys, to be described later.

A forwardly projecting arm 38 of each of the diverging levers 25 has an aligning rack 39 mounted thereon for engagement by an aligning bail (not shown) in known manner.

Digit keyboard

The keyboard, in which the digit keys for controlling the movement of the differential stop bars 23 are mounted, has a main frame including a top plate 40 (Fig. 2), and a bottom plate 41.

A typical keyboard row is represented in Fig. 2. The keys 42 have key stems slidably mounted in aligned slots cut in the top and bottom plates and are normally held in an upward position by springs 43. The depression of a key 42 causes its stem to be projected below the bot-

tom plate 41 so as to be in the path of an associated tooth on the stop bar 23 so that the latter will be arrested after a predetermined amount of movement during the first half of any entry cycle of the machine.

5 Provision may be made, in known manner, for an interlock between the 20 pounds key and the 8 and 9 pounds keys in order to prevent the direct entry of a quarter or more in terms of pounds.

The totalizer

The totalizer is mounted in a frame which carries a shaft 43a (Figs. 2 and 3), the totalizer wheels being rotatably mounted in spaced relation on said shaft. The units of pounds totalizer wheel comprises a ten-toothed pinion 44 (Fig. 2) while the tens of pounds wheel comprises a twelve-toothed pinion. The quarters totalizer wheel comprises an eight-toothed pinion wheel, while the hundred-weights and tons wheels each comprise a ten-toothed pinion.

10 All of the pinions have attached thereto, an indicator drum 45, that for the units of pounds wheel bearing the numerals "0" to "9," that for the tens of pounds wheels bearing the numerals "0" to "2" repeated four times about its periphery, that for the quarters bearing the numerals "0" to "3" repeated twice about its periphery, that for the units of hundred-weights bearing the numerals "0" to "9," and that for the tens of hundred-weights bearing "0" to "1" repeated five times about its periphery, while the remainder of the drums each bear the numerals "0" to "9" about their peripheries.

20 On the left-hand side of each indicator drum 45, is a transfer member, that for the units of pounds wheel being shown in detail in Fig. 4, and those of the tens of pounds, quarters, and tens of hundred-weights, being shown in Figs. 5, 6, and 7, respectively.

25 Referring to Figs. 4 and 11, the transfer member of the units of pounds wheel, includes a subtract tripping tooth 46, and an add tripping tooth 47 spaced counterclockwise of the subtract tooth at 30 degrees, and being offset leftwardly from the tooth 46 as viewed from the front of the machine, see Figs. 8 and 9.

30 The transfer member associated with the tens of pounds wheel 45, is provided with four subtract teeth 46 and four add teeth 47, as shown in Fig. 5, whereas the 35 pawl member for the quarters wheel has two subtract teeth and two add teeth, as shown in Fig. 6.

35 As will be seen from Fig. 7, the tens of hundred-weights transfer member has five subtract teeth and five add teeth. The units of hundred-weights wheel and the 50 remainder of the wheels i. e. the tons, each have pawl members similar to that shown in Fig. 4, i. e. one add tooth and one subtract tooth.

40 The totalizer shaft is movable from the right to the left and moves the totalizer correspondingly. In its right-hand position, that is, for adding, the pinions 44 of the totalizer wheels are aligned oppositely to the actuator racks 36 on the diverging levers 25. The machine employs the method of direct subtraction, and for this purpose there is associated with each totalizer pinion 44, an idler gear consisting of two pinions 48 and 49 (Figs. 2, 8 and 9), coupled by a sleeve 50 mounted on a short shaft 51 supported on the totalizer frame. The pinion 49 is in permanent engagement with the pinion 44, but when the totalizer frame is shifted to the left for subtraction, the 55 pinions 48 are aligned with the actuator racks 36.

45 Fig. 8 shows the disposition of the parts when the totalizer shaft is in the adding position, whilst Fig. 9 shows their disposition when the totalizer shaft has been moved into the subtraction position. The manner of control of the movements of the totalizer shaft is fully described in the Carlson et al., United States Patent No. 2,666,574, to which reference has been made.

50 As will be seen from Fig. 3, the toothed actuator racks 36 are each mounted on the upwardly extending arm of their associated diverging lever, by means of studs on

the latter engaging slots on the former, not shown in detail, such coupling permitting of relative movement of the rack forwardly by one step, from the normal position in which it is held by a spring 52, with the exception of the units of pounds and tens of pounds racks which are permitted a relative movement of two steps.

Dealing firstly with the lowest order, i. e. the units of pounds wheel, it will be seen that an abutment 53 extends laterally from the rack 36 and normally abuts against two stops 54 and 55 respectively formed on the right-hand ends of a pair of U-shaped brackets 56, 57.

The bracket 56 embraces the bracket 57, and both are pivoted on a shaft 58 passing between plates 59 (see also Fig. 2) supported on rods 60 and 61 secured in the frame side plates. The bracket 57 has its right-hand portion formed as a high surface 62 adapted to be operated upon by a cam 63 secured on the units of pounds totalizer pinion 44, the purpose of said cam being described hereinafter. In Fig. 2, the right-hand end of bracket 56 has been omitted for clarity.

It will also be seen from Fig. 3, that the upper edge of the right-hand end of each of the brackets 56, 57, is inclined as indicated at 64, and from Fig. 2, it will be seen that these angled portions are normally adapted to contact the underside of the rod 61, springs 65 urging said brackets upwardly, the upper end of the springs being anchored to a bridge 66 secured above the brackets.

As viewed in Fig. 3, the left-hand end of the bracket 57 is formed with a dependent portion 67 having an arcuate slot 68, while the left-hand end of bracket 56 is formed at right-angles to the main body so as to form an arm 69 which terminates in an upstanding portion 70 and is provided with a flat surface 71 the purpose of which will be described hereinafter.

A transfer lever 72 rockably mounted on the shaft 58, is provided in association with the lowest order, i. e. the units of pounds. This transfer lever has an outer offset portion 73 in alignment with the above-mentioned add transfer tooth 47 (see also Fig. 4) of the transfer member of the units of pounds order when the totalizer is in adding position.

A pivotally mounted latch is associated with each totalizer wheel, and that, 74, relating to the units of pounds wheel, is provided with an arm 75 and a lug 76 and is urged counter-clockwise by a spring 77.

The transfer lever 72, through a pin 78, is connected to a pawl 79 the nose of which is adapted to cooperate with a ratchet lever 80 pivotally mounted on the shaft 58 and shown in greater detail in Fig. 10, the pawl being urged into its operative position by means of a spring 81 which is anchored to the bridge 66.

Referring more particularly to Fig. 10, it will be seen that the ratchet lever 80 is substantially U-shaped near its forward end, one limb being provided with three steps 82 and a notch 83, while the other limb is provided with a pair of shoulders 84 and 85. As indicated diagrammatically in Figure 3, the front surface 86 of the ratchet lever 80 is normally in the path of an abutment 87 carried by the rack 36 associated with the tens of pounds totalizer wheel. Moreover, it will also be seen that the ear 75 of the latch 74 normally rests on the lowermost step 82 of the ratchet lever 80 and contacts a surface 88 of the transfer lever 72.

A transfer lever 89, also pivotally mounted on the shaft 58, is associated with the tens of pounds order, the nose 90 of said lever also being offset to align with the four add teeth 47 (see Fig. 5) of the transfer member of the tens of pounds wheel when the totalizer is in adding position. However, it will be seen from Fig. 3 that an upper edge of this transfer lever is provided with a pair of steps 91 while its lower edge is provided with a lateral extension 92 adapted to contact the flat surface 71 of the arm 69, and also to contact an abutment 93 carried by the quarters actuator 36.

A latch 94, associated with the tens of pounds totalizer

wheel is provided with an ear 95 and a lug 96, a spring 97 urging the latch counter-clockwise, whereby the ear 95 is normally adapted to rest upon the lowermost step 91 of the adjacent lever 89, as shown diagrammatically.

A lever 98, Figure 3, is pivoted, at 99, to the latch 94, and is provided with a stud 100 extending therefrom and located in the arcuate slot 68 in the depending arm 67 of the bracket 57.

The operation of the mechanism relating to the present invention will now be described.

Add operations

As described in the aforesaid United States Patent No. 2,666,574 of Carlson et al., at the commencement of each machine cycle, the transfer levers are all reset at zero.

Assuming that the machine has previously been cleared, and 7 pounds are entered into the machine, the amount will be registered on the units of pounds totalizer pinion in the usual way, so that the cam 63 thereon will be adjacent the surface 62 of the bracket 57.

Upon a further 1 pound, making a total of 8 pounds, being entered into the machine, the cam 63 will contact the surface 62 to rock the bracket 57 counter-clockwise about its shaft 58, thereby removing the stop 55 out of the path of the abutment 53 carried by the units of pounds rack 36. Simultaneously, the dependent portion 67 at the other end of the bracket 57 will move, thereby removing the rear face of the arcuate slot 68 from contact with the stud 100.

The surface 62 and the cam 63 are so related that the bracket 57 is retained depressed through positions 8 and 9 of the units of pounds totalizer wheel.

However, if a further 8 pounds are entered into the machine, making a total of 16 pounds, the cam 63 will ride off the surface 62, as the units of pounds totalizer pinion passes from its "9" to its "0" position, thereby permitting the spring 65 to return the lever bracket 57 to normal. As the units of pounds totalizer wheel passes from its "9" to its "0" position, the add tooth 47 (Fig. 4), will engage the offset portion 73 of the transfer lever 72 thereby rocking the latter about the shaft 58.

Through the medium of pin 78, the depression of the transfer lever 72 will cause the pawl 79 to depress the ratchet lever 80, thus permitting the ear 75 on the latch 74 to engage the next upper step 82 (Fig. 10) on said ratchet lever, under the influence of the spring 77, thereby maintaining the latter in its depressed position whereby the portion 86 of the ratchet lever will be moved out of the path of the abutment 87 of the tens of pounds rack 36, and the shoulder 84 moved thereinto.

Obviously, the tens of pounds rack 36 will now be permitted to move an extent equal to one tooth thereon, in other words, the totalizer pinion of the tens of pounds wheel will move from its "0" position to its "1" position. In the meantime, the units of pounds pinion will have reached its "6" position. Thus 16 pounds will now be registered on the totalizer.

At the commencement of the next machine cycle, the totalizer frame, as described above, will rock the totalizer latches in a clockwise direction. Such movement of the latch 74 will enable its ear 75 to contact the rear edge of the pawl 79, thereby similarly rocking the latter, which will remove its nose from engagement with the ratchet 80 which is thereupon moved upwardly by its spring 101. The ear 75 will thereupon restore to the lowermost step 82 of the ratchet 80, and the nose of the pawl will re-engage the notch 83 of said ratchet when the latch 74 is restored.

Simultaneously, in known manner, the bail 27, extending across the front of the diverging levers, will be removed, thus permitting the latter to move forwardly.

If a further 9 pounds are now entered into the machine, making a total of 25 pounds, the units of pounds totalizer will move from its "6" position to its "5" position, and in so doing, the bracket 57 will again be depressed

when the totalizer pinion is in its "8" and "9" positions, and returned as the latter moves from "9" to "0."

As the units of pounds totalizer pinion passes from "9" to "0," its add tooth 47 (see Fig. 4) will again depress the transfer lever 72 and cause the pawl 79 to depress the ratchet 80 in the manner described above. This latter movement enables the ear 75 of the latch 74 to engage the next upper step 82 (see Fig. 10) thus maintaining the ratchet 80 in a position where the shoulder 84 thereon will be in the path of the abutment 87 of the tens of pounds rack 36 and permitting the latter to move a distance equal to one tooth. The totalizer pinion of the tens of pounds will have now been rotated to "2."

However, as the tens of pounds pinion moves from its "1" position to its "2" position, its add tooth 47 (see Fig. 5) will contact the portion 70 of the arm 69 and rock the latter about its pivot point 58, thereby, at its opposite end, removing the stop 54 on the bracket 56 out of the path of the abutment 53 carried by the units of pounds rack 36.

In the meantime, the units of pounds wheel will have reached its "5" position. Thus 25 pounds will now be registered on the totalizer, and the condition is that the stop 55 is in the path of the abutment 53 of the units of pounds rack, while the stop 54 is held out of the path of said abutment.

As before, at the commencement of the next machine cycle, the transfer levers are reset, thus resetting the ear 75, pawl 79, and ratchet 80.

If now, a further 3 pounds are entered into the machine, making a total of 28 pounds, 1 quarter, 00 pounds will be registered on the totalizer. However, the units of pounds wheel will move to its "8" position, but in this case, means must be provided to add an additional "two" to move the wheel to "0." This requires a backward control from the tens of pounds wheels, and involves a "fugitive two" mechanism.

The means for adding the "fugitive two" will now be explained.

Taking the given example, it will be recalled that the stop 54 on bracket 56 is removed from the path of the units of pounds rack 36 when the tens of pounds pinion is in its "2" position, therefore, as the units of pounds totalizer wheel again passes from its "7" to its "8" position, the cam 63 on the units of pounds totalizer pinion will engage the surface 62 to remove the stop 55 from the path of the abutment 53 of the units of pounds rack 36. Thus both stops 54 and 55 will have been removed from the path of the abutment 53 thereby permitting the units of pounds rack to move a distance equal to two teeth on said rack, and entering the "fugitive two" into the totalizer.

When the units of pounds totalizer pinion now passes from its "9" position to its "0" position, its add tooth 47 will again depress the transfer lever 72 as described above, thereby causing the ear 75 to move into the first step 82 of the ratchet 80.

The add tooth 47 of the tens of pounds totalizer pinion wheel will, as the latter approaches its zero position, contact the nose 90 of the transfer lever 89 and depress same.

Depression of the transfer lever 89 will remove the lateral extension 92 (see Fig. 3) thereon from the path of the abutment 93 carried by the quarters rack 36 and thereby permit the latter to move an extent equal to one tooth thereon, thus causing "1" to be entered into its totalizer wheel.

In the meantime, the units of pounds wheel will have reached its "0" position. Thus the amount shown in the totalizer will be 1 quarter 00 pounds.

When the quarters totalizer has reached its capacity i. e. "3" it will pass from "3" to "0" and in so doing, will transfer "1" to the units of hundred-weights totalizer wheel in known manner. Similarly, when the latter passes through "9" to "0," it will add "1" to the tens of hundred-weights totalizer wheel and so on to the "tons" wheels, throughout the machine.

Where the tens of pounds pinion wheel is actuated independently of the units of pounds wheel, such e. g. as when 10 pounds are added to 20 pounds, making a total of 30 pounds, the "fugitive two" is automatically entered into the units of pounds totalizer wheel.

As explained above, when the tens of pounds totalizer pinion is standing at "2," the add tooth 47 thereon, will maintain the lever arm 69 depressed, and thus the stop 54 will be disabled. As the tens of pounds totalizer pinion passes from "2" to "0," the add tooth thereon, contacts the nose 90 of the transfer lever 89 and thereby depresses the latter. The first step 91 of the transfer lever is thus moved from the path of the ear 95, which permits the latch 94 to rotate counterclockwise under urgency of its spring 97 to move the said ear into the second step 91 of the transfer lever 89 and maintain the latter in its depressed position, and in so doing, the lateral portion 92 thereof, due to its contact with the upper edge of the lever arm 69, will maintain said arm in its depressed position. Also the stud 100 on lever 93 similarly rocks the bracket 57 thereby to remove the stop 55 from the path of the abutment 53 carried by the units of pounds rack.

As both stops 54, 55 have now been removed, the units of pounds rack is permitted a movement equal to two teeth, or in other words the "fugitive two" will be entered into the units of pounds totalizer, which, in this example, will move to "2." Thus the indicator 11 would show a reading of 1 quarter 02 pounds.

Obviously owing to the depression of the transfer lever 89, the lateral portion 92 thereof will have been removed from the path of the abutment 93 on the quarters rack 36, thereby permitting the latter to move a distance equal to one tooth and thus entering one unit into the quarters totalizer wheel.

A further condition arises, in connection with the rotation of the units of pounds and tens of pounds totalizer wheels, where 9 pounds or 19 pounds are standing in the totalizer, and 19 pounds or 9 pounds are added thereto, respectively.

For example, if 19 pounds are standing in the totalizer and 9 pounds are added thereto, the units of pounds wheel, as it approaches zero, will transfer one unit into the tens of pounds totalizer pinion as described.

The tens of pounds pinion wheel will therefore move from "1" to "2" to depress the lever arm 69 thereby to move the stop 54 from the path of the units of pounds rack.

The units of pounds totalizer pinion wheel will then advance to its "8" position, whereupon the cam 63 will contact the surface 62 thus disabling the stop 55. Hence both stops 54 and 55 will now be out of the path of the units of pounds rack thus enabling the latter to move an extent equal to two teeth and thereby entering the "fugitive two" therein.

As the "fugitive two" is entered, the add tooth of the units of pounds pinion will cause depression of the ratchet 80, and hence the advancement of the tens of pounds pinion from "2" to "0" and the quarters wheel from "0" to "1" will take place as described.

Thus the indicator 11 would show 1 quarter 00 pounds.

Subtract operations

Firstly, as fully described in the aforesaid United States patent of Carlson et al., No. 2,666,574, the totalizer is conditioned for subtract entries by moving the totalizer to the left to bring the pinions 48 of the idler gears into alignment with the actuator racks 36 and the subtract teeth 46 of the transfer members into alignment with portions 102, 103 (see Figs. 4-9) of the transfer levers.

Movement of the shaft will remove the cams 63 from alignment with the surface 62 and similarly the add tooth 47 of the tens of pounds pinion will be moved out of alignment with the upstanding portion 70 of the arm 69.

However, the stops 54 and 55 of the brackets 56, 57,

will still be in alignment with the abutment 53 carried by the units of pounds rack 36, or in other words, the latter will be prevented from making the fugitive transfer movement.

Thus, assuming that a positive quantity of three pounds is standing in the totalizer and it is desired to subtract 6 pounds therefrom, the units of pounds totalizer wheel will rotate in the opposite direction, and as said wheel approaches zero, the subtract tooth 46 thereon will cam down on the surface 102 (see Fig. 3) on the transfer lever 72 to cause a negative transfer into the tens of pounds totalizer pinion, thus rotating it to "2." A negative entry into the tens of pounds totalizer pinion will cause the subtract tooth 46 thereon to cam down on the surface 103 formed on the transfer lever 89. This permits the lateral extension 92 on said lever 89 to bear down upon the surface 71 of the arm 69 thus rocking the bracket 56 about its pivot point 58 thereby removing the stop 54 from the path of abutment 53.

Owing to the depression of the transfer lever 89, the ear 95 of latch 94 will move onto the second step 91 of said lever, and hence the movement of the latch 94 in a counterclockwise direction will cause the stud 100 on lever 98 to contact the rear edge of the arcuate slot 68 and thereby urge the dependent portion 67 of bracket 57 also in a counterclockwise direction. Such movement of the bracket 57 will remove the stop 55 thereon from the path of the abutment 53 carried by the units of pounds rack 36.

It will be appreciated that as both of the stops 54 and 55 are now disabled, the units of pounds rack will be permitted a movement equal to two teeth thereon, thus subtracting the "fugitive two" from the units of pounds order, which will then move to its "5" position.

Also, depression of the transfer lever 89 will transfer to quarters, which in passing from 0-3, transfers negatively to the next highest order which is repeated up to the highest order of the machine, whereby the totalizer will register the complement of the true figure; that is, 9999919325.

A further condition arises, in connection with the rotation of the units of pounds and tens of pounds totalizer wheels in subtract operations, where certain combinations of figures are in question.

For example, if 1 quarter 10 pounds is standing in the totalizer, assuming that the last entry was an add entry, and it is desired to subtract 19 pounds therefrom, this amount is entered into the keyboard in subtraction.

During the ensuing operating cycle of the machine, the bail restraining the diverging levers will be allowed to move, and the latter, being under spring tension, will move forwardly, until their associated stop-bars 23 contact the appropriate depressed keys, i. e. "1" and "9," bearing in mind, of course, that the two lowermost orders of the actuator racks 36 are spring loaded one position forwardly from the remainder of the racks, making a total of two positions from zero. Thereafter the totalizer will be engaged with the racks, and the subtract transfer teeth 46 on each totalizer pinion wheel will be aligned with the cammed surfaces of the transfer levers. Subsequently, the bail 27 restores the diverging levers, and hence the racks move rearwardly, but in the example given the bail 27 will firstly contact the units of pounds diverging lever which will rotate the units of pounds totalizer pinion in the reverse direction thus permitting the subtract tooth 46 thereon, as the pinion moves from "0" to "9," to cam down on the surface 102 of the transfer lever 72. Depression of the latter will subtract one unit from the tens of pounds wheel and cause the pawl 79 to depress the ratchet 80 thus allowing the ear 75 of latch 74, to move up one step 82 on said ratchet. This condition ensures that the ratchet 80 will be latched in its depressed position thus removing the abutment 86 out of the path of the tens of pounds rack and thereby placing the shoulder 84 of the

ratchet, into the path of the abutment 87 which will thereby permit a further unit to be subtracted from the tens of pounds totalizer, i. e. the latter pinion will then be standing at "2."

5 The subtract tooth 46 on the tens of pounds totalizer pinion will then depress the transfer lever 89 thus permitting the ear 95 to move up onto the step 91 of said lever, the lateral extension 92 of the latter contacting the surface 71 of the lever arm 69 which is thereby 10 caused to rock in a counterclockwise direction thus ensuring that the stop 54 is removed out of the path of the abutment 53 carried by the units of pounds rack 36.

Simultaneously as extension 92 moves from the path of the abutment 93 of the quarters wheel one unit will 15 be subtracted from the quarters wheel thus returning it from "1" to "0."

By reason of the ear 95 being permitted to move up onto the step 91 of the transfer lever 89, the stud 100 will urge the bracket 57 in a counter-clockwise direction 20 thereby removing the stop 55 into its inoperative position. As both stops 54 and 55 will now be in their inoperative position, the units of pounds rack will thus be permitted to move an extent equal to two teeth thereon, or, in other words, the "fugitive two" will be subtracted from the lowest order wheel which will move 25 from "1" to "9."

During this latter movement of the units of pounds totalizer pinion wheel, the subtract tooth 46 thereon will again depress the transfer lever 72 thereby permitting 30 the nose of the pawl to engage the first step 82 of the ratchet 80 and depress the latter still further thus permitting the ear 75 of latch 74 to move up yet another step 82 (see Figure 10). Thus the riser of the shoulder 85 (Fig. 10) will be placed in the path of the abutment 87 35 of the tens of pounds rack. This will permit said rack to move yet a further distance equal to one tooth. Thus the tens of pounds totalizer pinion will now move from "2" to "1." The amount now shown in the indicator 11 will be 0000000019.

40 What is claimed is:

1. A machine for effecting calculations according to the avoirdupois system of measurement, including a totalizer and actuators therefor, the units of pounds actuator normally adding up to "nine" but being capable of 45 an additional movement to add an additional amount into the units of pounds totalizer wheel, transfer mechanism associated with the units of pounds totalizer wheel, and a pair of stop-members adapted to engage an abutment on the units of pounds actuator and thereby prevent the additional movement thereof, one of said members being under the control of the units of pounds totalizer wheel and disabled when said wheel passes through its "eight" and "nine" positions, whilst the remaining member is disabled when the tens of pounds 50 totalizer wheel is in its "two" position, thereby enabling the units of pounds actuator to make the additional movement to advance the units of pounds totalizer wheel to "zero" or beyond, dependent upon the amount entered in the units of pounds order.

2. A machine according to claim 1, wherein the stop-members each comprise a pivotally mounted lever spring biased into operative position, one of said levers having that end of it which is remote from the abutment, co-operating with the tens of pounds totalizer wheel when 55 the latter is in its "two" position, while the second lever has that end of it, adjacent the abutment, formed as a high surface which is operated upon by the units of pounds totalizer wheel as the latter passes through its "eight" and "nine" positions.

3. A machine according to claim 1, wherein the units of pounds actuator is provided with an abutment normally cooperating, for additive entries, with one or both of the stop members to prevent the additional movement of said actuator when the tens of pounds totalizer wheel is standing at less than "two."

11

4. A machine according to claim 3, wherein the totalizer is provided, in each denominational order, with a single main pinion engageable directly with its actuator for adding operations, an auxiliary double pinion mounted on the totalizer frame one set of whose teeth engage directly with the main pinion and the other set of whose teeth lie out of the plane of the actuator during adding operations, selectively operable mechanism for shifting the totalizer frame transversely of the actuators to align said other set of teeth therewith for subtract operations, at least one pair of transfer teeth mounted integrally with the main pinion and offset from one another in the direction of shift of the totalizer, and a common transfer tripping lever having an add portion and a subtract portion offset similarly to the transfer teeth so as each to cooperate with a related one of said teeth when the frame has been shifted to adding or subtracting position, respectively.

5. A machine according to claim 4, wherein a latch is provided in association with each transfer tripping lever, each of said latches being provided with an ear adapted, when the transfer tripping levers are depressed by the transfer teeth to engage with a step formed on each of the latter levers, with the exception of that associated with the units of pounds totalizer wheel, thereby to maintain said levers in a depressed condition until the latches are automatically restored at the commencement of each machine cycle.

6. A machine according to claim 5, wherein the frame supports a shaft upon which the stop-levers and transfer tripping levers are pivotally mounted, a spring biased ratchet also being mounted on said shaft adjacent the transfer tripping lever associated with the units of pounds totalizer wheel to effect latching of the latter lever in its depressed condition.

7. A machine according to claim 6, wherein the ratchet is provided with a plurality of steps, a notch, and three stop-surfaces, one of the latter being adapted, when the ratchet is in normal position, to contact an abutment carried by the tens of pounds actuator and thereby limit movement thereof as required for normal additive and subtractive operations.

8. A machine according to claim 7, wherein the three stop-surfaces are located a predetermined distance away from each other, both longitudinally and vertically, to control a single, or double, transfer into the tens of pounds totalizer wheel.

9. A machine according to claim 8, wherein the transfer tripping lever, associated with the units of pounds totalizer wheel, has a spring-biased pawl pinned thereto the nose of which, when the ratchet is in normal position, is adapted to be located within the notch of said ratchet, the ear of the related latch being located between the rear edge of the pawl and the lowermost step of the ratchet.

10. A machine according to claim 9, wherein as the units of pounds totalizer wheel passes from its "nine" position to its "zero" position, the add transfer tooth thereon will depress the associated transfer tripping lever and thus enable the pawl to depress the ratchet whereby the second step thereon will engage with the underside of the latch-ear, said ratchet thereby being maintained in a depressed condition until the next machine operation.

11. A machine according to claim 10, wherein when the ratchet is so depressed, the first stop-surface thereon will be moved out of the path of the abutment on the tens of pounds actuator and the second stop-surface placed therein, thus permitting the said actuator to move an extent equal to one tooth thereon.

12

12. A machine according to claim 11, wherein when the totalizer latches are rocked at the commencement of each machine cycle, the pawl will be rocked by the latch associated with the units of pounds actuator thus permitting the ratchet to be restored under spring tension whereupon the nose of the pawl will re-engage with the notch in ratchet.

13. A machine according to claim 12, wherein, for add operations, the main totalizer pinion related to the units of pounds, is provided with a cam adapted, when the said pinion passes through its "eight" and "nine" positions, to cam down upon the high surface formed on the second stop-lever, thereby pivoting the latter and rendering the second-stop inoperative.

14. A machine according to claim 13, wherein, for add operations, as the tens of pounds totalizer wheel passes from its "one" position to its "two" position, the relevant add transfer tooth thereon depresses the first stop-lever thereby causing the first-stop to be rocked into an inoperative position, and thus permitting the units of pounds actuator, when the totalizer wheel relating to the latter is passing through its "eight" and "nine" positions, to move an extent equal to two teeth thereon to add a "fugitive two" into the units of pounds totalizer.

15. A machine according to claim 14, wherein the transfer tripping lever associated with the tens of pounds totalizer wheel is provided with a lateral extension normally located in the path of an abutment carried by the quarters actuator whereby, when said transfer tripping lever is depressed as the tens of pounds totalizer wheel passes from its "two" position to its "zero" position, the quarters actuator will be permitted to move an extent equal to one tooth thereon to register one unit into the quarters totalizer.

16. A machine according to claim 15, wherein the transfer tripping lever associated with the tens of pounds totalizer wheel is provided with a lateral extension co-operating with the first stop-lever, whereby when the said tripping lever is depressed, the lateral extension will depress the first stop-lever thus removing the first-stop from the path of the units of pounds actuator.

17. A machine according to claim 16, wherein the latch associated with the tens of pounds transfer tripping lever is provided with an arm having a stud formed in the second stop-lever, said stud, when the latch-ear moves up on to its related step of the transfer tripping lever and by reason of its contact with the rear edge of the slot, serving to rock the second stop-lever thus removing the second-stop from the path of the units of pounds actuator.

18. A machine according to claim 17, wherein entry of the "fugitive two" is achieved when the units of pounds totalizer wheel passes from "nine" to "zero," whereupon the latter wheel will transfer one unit into the tens of pounds totalizer wheel, and hence when the latter wheel moves from its "one" position to its "two" position, the transfer tooth thereon will depress the first stop-lever thereby removing the first-stop from the path of the units of pounds actuator, the units of pounds totalizer wheel, as it passes through its "eight" and "nine" positions, permitting the cam to depress the second stop-lever and thereby removing the second-stop from the path of the units of pounds actuator to allow the latter to move an extent equal to two teeth thereon.
